UNITED STATES PATENT OFFICE.

OLIVER F. CONKLIN, OF DETROIT, MICHIGAN, ASSIGNOR TO REMY ELECTRIC COMPANY, OF ANDERSON, INDIANA, A CORPORATION OF INDIANA.

IGNITION APPARATUS.

Application filed September 19, 1917. Serial No. 192,057.

To all whom it may concern:

Be it known that I, OLIVER F. CONKLIN, a citizen of the United States, residing at Detroit, in the county of Wayne and State 5 of Michigan, have invented certain new and useful Improvements in Ignition Apparatus, of which the following is a full, clear, and exact description.

This invention relates to certain new and 10 useful improvements in ignition devices and more particularly to improvements in the breaker devices for the primary ignition circuit, which device is commonly called the timer. Other improvements reside in 15 the provision of a novel cam advancing mechanism which is adapted to advance the time of ignition in accordance with changes in engine speed. The improvements in the spark advancing mechanism provide a 20 structure which is adapted to produce the proper spark advance for a wide range of engine speed and power conditions. Furthermore, the spark advancing device is reversible, so that by a slight rearrangement 25 it may be made to operate in either a clockwise or counter-clockwise direction of rotation.

With these and other objects in view which will be pointed out more in detail 30 in the accompanying specification and claims, the preferred embodiment of the invention will now be described.

In the drawings:

Fig. 1 shows in central section a timer 35 distributor having the improved breaker devices and spark advancing mechanism.

Fig. 2 shows a top plan view of the breaker structure mounted upon its supporting plate and in operative relation to 40 the timer cam.

Fig. 3 shows a top plan view of the spark advancing mechanism with the parts in the position they occupy when the timer is at rest.

Fig. 4 shows the position of the spark advancing mechanism parts in fully advanced position.

In more detail in the drawings, 10 is the timer casing having dowels 11 to locate the 50 timer plate 12 and the distributor cap 13. The distributor is preferably of the type shown in Conklin Patent No. 1,372,065, issued March 22, 1921, and is secured to the casing by means of the spring clips 14. The 55 engine driven shaft 15 is journaled in the

depending part of the casing and at its upper end the shaft has secured thereto to rotate in unison therewith a circular plate 16. Three equally spaced pins 17 are carried by this plate and project upwardly therefrom to form the pivots for three centrifugal weights 18. Each of these weights carries a rivet member 19 rounded at each end so as to form a frictionless support for the weight upon the plate 16 and to permit each 60 weight to move about its pivot without bending. To reduce the friction to a minimum, preferably the weight rivet and the plate are both hardened. The weights are preferably spaced from the plate adjacent 65 the pivots by washers 20.

Coaxial with the engine shaft 15 and preferably integral therewith is a shaft 21 which extends above the plate 16 and the plane of weights 18. This shaft forms a bearing 75 or journal for a sleeve member 22 to which is attached a spider member having three arms 23. Also attached to the sleeve is a timer cam 24. Each centrifugal weight 18 has a tail piece 25 which projects in toward 80 the center of the shaft 21 and cooperates with a cam edge 26 on the spider arms 23. Each spider arm 23 has two symmetrical cam edges 26 and this permits the weights to be turned over so that the tail pieces will 85 cooperate with the opposite sides of the spider (see dotted line construction in Fig. 3). This permits the same parts to be used with either a clockwise or counterclockwise rotation. The spider arms 23 each carry 90 pins 27 which form supports for springs 28, which at opposite ends connect with pins 17. The pins 27 project through the spider arm into arcuate slots 29 of the plate 16. The pins 27 cooperate with the end of the 95 slots 29 and limit the extreme outward movement of the weights (see Fig. 4). The extreme inward movement or position of the weights is limited by the rear edges of the tail pieces contacting with the edges of 100 the weights (see Fig. 3).

With a centrifugal device for advancing the spark, the centrifugal force increases as the square of the radius of the mass center from the center of rotation and also directly 105 as the speed increases. From an inspection of Fig. 3 it will be seen that the line of action of springs 28 is radial, in which direction they exert little restraint upon the outward movement of the weights; also the 110

tail pieces exert their greatest leverage upon the spider arms. As the weights move outwardly, the tail pieces cam against the cam edges 26 of the spider arms 23 and advance the spider sleeve and timer cam 24 angularly with respect to the engine shaft. In this way the spark advance is effected. As the spider is advanced, the springs 28 act in a manner so as to effect a greater and greater restraint upon the advance of the spider. Concurrently also tail pieces 25 exert less and less leverage on the spider cam edges 26, and by these coacting means the excessively great centrifugal advancing action 15 is compensated for. Furthermore, the spark advance for a particular set of engine conditions can be controlled by changing the contour of the cam edge 26 of the spider arms 23, or by changing the contour of the 20 coacting edges of the tail pieces 25. Once the proper contour is determined for a particular engine the parts may be easily duplicated and the spark advance will be the same for each complete apparatus. It will 25 also be understood that the spark advancing action may be varied by replacing springs 28 with other springs having a different tension.

It will be apparent from the drawings 30 that the surfaces of the tail pieces 25 and the cam edges 26 of the spider 23 are formed so as to obtain a direct rolling contact, whereby friction will be reduced.

35

Timer construction.

The timer or breaker comprises a base plate 30, preferably a stamping, which is secured to plate 12 but insulated therefrom by means of a strip of insulation 31. The 40 base plate 30 has an integral struck up portion 32 to which is secured a strip of insulating material 33, such as "Dilecto". This strip 33 forms the fulcrum for the breaker lever 34, which is preferably of sheet metal 45 and formed into a channel section so as to be rigid and very light in weight. A copper strap or jumper 35 conducts the current from the insulated base plate 30 to the breaker lever 34. The base plate 30 also has struck up posts 36 and 37, one of which, namely 36, forms an abutment to support the breaker lever when the plate 30 is removed, and the other, namely post 37, forms an abutment to which the other end of a coil spring 39 is attached. The opposite end of the coil spring is attached to an eye in the breaker lever, whereby contact 40 carried by the lever is normally maintained in contact with the adjustable contact 41. This 50 adjustable contact is carried by a post 42 struck up from a plate 43 which is fastened to and in electrical connection with base plate 12. A screw (shown in Fig. 2) secures the plate 43 to the base plate.

In order to move the breaker lever against

the action of the restraining spring in order to periodically open the primary ignition circuit at the contacts 41 and 40, the end 44 of the breaker lever is bent over at an angle and carries a piece of insulating material, such as "Dilecto", which normally is in practically tangential contact with cam 24. As the cam rotates the breaker lever is rocked about its fulcrum to effect a break of the circuit at the contacts 40, 41. The breaker lever is a lever of the second order, the cam supplies the force at the free end of the lever while the spring (weight element) is located between the cam and the fulcrum.

The spring 39 therefore maintains the lever upon its fulcrum in either open or closed position of the cam. The strap 35 operates in conjunction with the spring and the action of the cam upon the rubbing block to maintain the lever upon its fulcrum.

A certain pressure between the timer contacts is always required in order to insure flow of current during the time of make of the ignition circuit. This is produced by the action of a spring. As a result, this spring produces pressure between the cam and rubbing block tending to wear the surfaces of both and particularly the latter. By placing the contacts between the rubbing block and the breaker lever fulcrum, the pressure of the rubbing block upon the cam is much less than where the rubbing block is located between the contacts and the fulcrum. Therefore by virtue of the construction and arrangement described, the wear on the rubbing block is reduced.

The condenser which is used to minimize the sparking at the contacts, is preferably contained in a metal case 46 secured to the base plate at one side of the cam. One side of the condenser within the case is connected to plate 30 by a strap 47, and the other side of the condenser is grounded on the base plate.

The high tension distributing apparatus need not be described here in detail, as it is fully described in the application heretofore referred to. It is sufficient to state that block 50 is a block of insulating material and carries the distributor for the high tension electric current.

What I claim is:

1. A timer for ignition apparatus comprising a rotatable cam, a breaker lever fulcrumed at one end upon a fixed part, and cooperating at its opposite end with the rotatable cam, a stationary contact carried by a fixed part and located between the cam and fulcrum, a cooperating contact carried by the breaker lever and disposed between the ends thereof, and a retractile coil spring for normally maintaining the contacts in engagement fastened at one end to a fixed part and at its other end to the breaker

lever, the point of fastening being intermediate the contacts and the fulcrum of the lever, whereby the spring will maintain the lever upon its fulcrum in either the open or closed position of the contacts.

2. A timer for ignition apparatus comprising a rotatable cam, a breaker lever fulcrumed at an end remote from the timer cam and having a block at the opposite end disposed obliquely to the plane of the breaker lever, said block adapted to rub on said rotatable cam and extending substantially tangential thereto, a stationary contact, and a cooperating movable contact disposed on the breaker lever between the fulcrum and the block, and a retractile coil spring attached to the breaker lever intermediate the contacts and the fulcrum thereof for maintaining the rubbing block in proximity to the cam and the contacts normally closed except when opened by the cam, for maintaining the lever upon its fulcrum in either the open or closed position of the contacts; and a flexible strap connected to a fixed part and to the lever, said strap operating in conjunction with the operation of the cam upon the block to maintain the lever upon its fulcrum.

3. A timer for ignition apparatus comprising a rotatable cam, a breaker lever fulcrumed at an end remote from the cam and having a block at the opposite end disposed obliquely to the plane of said lever, said block adapted to rub on said cam and extending tangential thereto, cooperating timer contacts one of which is carried by the lever, a spring connected with the lever for maintaining the contacts normally in engagement, a flexible strap connected with the lever and a fixed part, said spring and strap operating in conjunction with the action of the cam upon the block to maintain the lever upon its fulcrum.

4. A timer for ignition apparatus comprising a rotatable cam, a breaker lever of the second order having one end cooperating with said cam, a coiled retractile spring fastened to said lever intermediate its ends and to a fixed part of the ignition apparatus, a contact carried by said lever intermediate the ends thereof, a cooperating contact, said contacts being normally closed by the said spring and being periodically opened to interrupt the primary circuit therethrough by the cam acting upon the breaker lever.

5. A timer for ignition apparatus comprising a rotatable cam, a base plate, a sub-base plate fastened thereto, a plurality of posts projecting upwardly therefrom, one of said posts carrying a block forming a fulcrum for a breaker lever, a second of said posts forming a support for one end of a spring, a third of said posts forming a limiting abutment for said breaker lever, a sec-

ond sub-base plate carrying a contact, a breaker lever fulcrumed at one end on the aforesaid fulcrum-block and contacting at its opposite end with the rotatable cam, a contact on said breaker lever cooperating with the aforesaid contact, and a retractile spring connecting the breaker lever and the aforesaid post and normally maintaining the contacts closed except when opened by the action of the cam on the breaker lever.

6. In an ignition apparatus, the combination with an engine driven shaft; of a timer cam adapted to be advanced angularly relatively thereto; centrifugal weight devices pivoted on a member attached to the engine driven shaft, and provided with tail pieces; a spider carrying the timer cam and provided with camming surfaces cooperating with said tail pieces, said surfaces and tail pieces being arranged so that the point of action therebetween moves toward the axis of the spider as the weights move outwardly with increasing speed; and coiled springs connecting the spider with said member, said springs being arranged so that the leverage thereof with respect to the spider substantially increases as the weight members move outwardly from the shaft.

7. In an ignition apparatus, the combination with an engine driven shaft; of a timer cam adapted to be advanced angularly relatively thereto; centrifugal weight devices pivoted on a member attached to the engine driven shaft, and provided with tail pieces; a spider carrying the timer cam and provided with camming surfaces cooperating with said tail pieces, said surfaces and tail pieces being arranged so that the point of action therebetween moves toward the axis of the spider as the weights move outwardly with increasing speed; and coil springs connecting the spider and said member, said springs being arranged substantially radially with respect to the axis of the spider, whereby initially to exert comparatively little restraining force upon the advancing movement of the spider.

8. In an ignition apparatus, the combination with an engine driven shaft; a weight supporting member carried by said shaft; a plurality of centrifugal weights having camming portions mounted upon studs carried by said member; a timer cam journaled for rotation axially of said shaft; radially extending camming arms connected with said timer cam and cooperating with said camming portions, said portions and arms being arranged so that as the weights move outwardly from the cam, the points of action between said portions and said arms will move toward the cam axis; and coil springs connecting said arms with said studs, said springs initially extending substantially radially with respect to the

cam axis, whereby initially to exert comparatively little restraining force upon the advancing movement of the spider.

9. In an ignition apparatus, the combination with an engine driven shaft; a weight supporting member carried by said shaft; a plurality of centrifugal weights having camming portions mounted upon studs carried by said member; a cam advancing 10 spider mounted upon said shaft for angular displacement relatively thereto and provided with radially extending camming arms, said arms and said camming portions of the weights being arranged so that as the 15 weights move outwardly from the cam, the points of action between said portions and said arms will move toward the cam axis; and coil springs connecting said arms with said studs, said springs initially extending 20 substantially radially with respect to the cam axis, whereby initially to exert comparatively little restraining force upon the advancing movement of the spider.
10. In an ignition apparatus, the combination with an engine driven shaft; a weight supporting member carried by said shaft; a plurality of centrifugal weights having camming portions pivotally mounted upon said member; a timer cam journaled for 25 rotation axially of said shaft; outwardly extending camming arms connected with said timer cam and cooperating with said camming portions, said portions and arms being arranged so that as the weights move outwardly from the cam, the points of action 30 between said portions and said arms will

move toward the cam axis; and coiled springs connecting the cam with said member, said springs being arranged so that the leverage thereof with respect to the spider 40 substantially increases as the weight members move outwardly from the shaft.

11. In an ignition apparatus, the combination with an engine driven shaft; of a timer cam adapted to be advanced angularly relatively thereto; a weight member attached to said shaft and in driving relation to said cam, said weight member and said cam having coacting lever arms so arranged that the leverage of the weight with respect to the cam will decrease as the cam is advanced; and a spring opposing the advancing 45 of the cam, the leverage of said spring increasing as the cam is advanced.

12. A timer for ignition apparatus comprising a rotatable cam, a breaker lever fulcrumed at one end upon a fixed part, and cooperating at its opposite end with a rotatable cam, a stationary contact carried by a fixed part and located between the cam and fulcrum, a cooperating contact carried by the breaker lever and disposed between the ends thereof, and a spring cooperating with said lever for normally maintaining the contacts in engagement, the leverage of said 50 spring with respect to said fulcrum being less than the distance from the contacts to the fulcrum.

In testimony whereof I hereunto affix my signature.

OLIVER F. CONKLIN.
